SWITCH CONTACT CONSTRUCTION

William H. Linda, St. Louis, Mo., assignor of one-half to Eola Linda and one-half to Joseph P. Pohrer

Application August 22, 1946; Serial No. 692,341

5 Claims. (Cl. 200—166)

1

This invention relates in general to certain new and useful improvements in electrical switches and, more particularly, to those of the knife type. The usual knife switch comprises a single blade for each circuit to be made or broken, that is, a single-pole switch comprises one blade hingedly engaged at one end between contacts, pressing against both sides of the blade, which end is called the "hinge jaw," and rotatably engaging and disengaging at the other end opposed spring contacts, called the "break jaw." In my invention, however, a pair of parallel blades is employed, which engage between them, at both the "hinge" and the "break" ends, clips with spherically-rounded contact faces.

The primary object of the present invention is to provide a double knife-type electrical switch with spherical contact surfaces interposed between the blades at both the "hinge" and the "break" ends.

A further object of the present invention is to provide a switch having a plurality of spherical contact surfaces which in the actuation of the switch connect and disconnect quickly and positively.

An additional object of the present invention is to provide a switch with spherically-formed contact or bearing points reinforced with silver or other metal suitable for long-wearing electrical contacts.

Another object of the present invention is to provide a high-capacity electrical switch whose current-transmitting parts may be economically fabricated from flat metal, and are readily assembled and easily replaced.

A further object of the present invention is to provide a switch of the type stated having air ventilated contact posts for readily dissipating heat generated by contact arcing and current conduction.

The above and other objects will become more fully apparent from the following specification, which, by way of illustration rather than limitation, sets forth preferred processes and preferred forms of apparatus constituting embodiments of the present invention, the scope of which is defined in the appended claims.

In the accompanying drawings:

Figure 1 is a top plan view of a switch constructed in accordance with and embodying my invention;

Figure 2 is a side elevational view of the switch, the "open" or disconnected position thereof being indicated in dot-dash lines;

2

Figure 3 is a vertical sectional view taken along line 3—3 of Figure 2; and

Figure 4 is a vertical sectional view taken along line 4—4 of Figure 2.

Referring now in more detail and by reference characters to the drawings which illustrate a preferred embodiment of the present invention, A designates a switch comprising two pot-type, porcelain insulators 1 conventionally mounted in a suitably spaced relation upon the steelwork of a transmission tower or some other supporting structure (not shown). Molded, or otherwise mounted in and projecting upwardly from the insulators 1 are studs 2, and mounted thereon by means of nuts 3 are copper terminal blocks 4 having binding posts 5 for the attachment of bus-bars 6. The inner ends of terminal blocks 4 are provided with a pair of parallel milled slots 7 for tightly receiving upright contact posts 8, the latter being retained therein by press-fitted pins 9 passing through laterally drilled apertures 10, 10' in contact blocks 4 and posts 8, respectively.

Each of said contact posts 8 consists of two halves symmetrically formed from flat copper stock, their upper end-portions 11 being bent inwardly and mitered to bear tightly against each other and thereby be retained in spaced parallel relation to permit the free circulation of air 30 therebetween for "ventilation" purposes. Beneath their inwardly bent upper end-portions 11, the contact posts 8 are outwardly drawn, pressed, stamped or embossed in the provision of protruding spherical portions 12 at the outer, or contacting, surfaces of which are silver inserts 13. Each pair of matching spherical portions 12 of the two symmetrically opposed halves of each post together form a substantially ball-like contact, the surface of which is concentric with the vertical plane along which the mitered upper end-portions 11 meet. In the preferred embodiment shown, there are four such ball-like contacts, although more or less than four may readily be employed where desired.

It will be noted that the posts 8 fixedly attached to the insulators 1 at both the "hinge" end (shown at right in Figure 1) and the "break" end (shown at left in Figure 1) are substantially identical. However, at the so-called "hinge" end, contact post 8 is laterally drilled as at 14 to receive hinge bolt 15 which, by means of radially split spring washers 16 and nut 17, holds the blades 18 with adjustable tension against the silver contact inserts 13 of the contact post 8 at that end. At 55 the other, or "break" end, terminal block 4 is

tapped to receive bolts 19 securing to it the fixed latch keeper 20.

The "break" ends of blades 18 are laterally drilled near their extremities to receive bolt 21 which, together with nut 22, holds between said blades 18 a channel-shaped spacer 23 and a rockably mounted latch lever 24 having a hook 25 adapted to engage the latch keeper 20. At its upper end, the latch lever is provided with a ring-shaped latch handle 26. Bolt 21 also passes through, and together with nut 22 holds adjacent to the outer surfaces of blades 18, leaf springs 27 having bent outer ends 28 and inwardly protruding embossed spherical portion 29 whereby to space said springs 27 with reference to the outer surfaces of blades 18. Also mounted in and extending through the "break" ends of blades 18 is a bolt 30 provided at its threaded end with a nut 31 for connecting the inner ends of leaf springs 27. By adjusting nut 31, any desired amount of spring pressure may be exerted by the inwardly-extending spherical portions 29 of springs 27 against the outer surfaces of blades 18 in the vicinity of the engagement and electrical contact of their inner surfaces with the interposed contact post 8 at the "break" end of the switch.

The method of assembly and disassembly of the switch for the replacement of parts is apparent from the construction shown and correct alignment of the parts follows inherently from the spring pressures against the several spherical contact surfaces.

Switches constructed as disclosed herein, whether of the single-pole single-throw type as illustrated or of more complex detail, as of multiple-pole, double-throw type, operate with a minimum of friction, due to the ball-like contacts. This permits higher contact pressures, which, together with the self-aligning feature, results in more positive electrical contact than would otherwise be possible. At the "break" end of the switch, the movement of the blades into and out of engagement with the several spherical contact faces is progressive, so that the contact is made and broken quickly.

It should be understood that changes and modifications both in the methods as well as in the form, construction, arrangement and combination of the several parts of the switch may be made and substituted for those herein shown and described without departing from the nature and principle of the present invention.

Having thus described my invention, what I claim and desire to secure by Letters Patent is:

1. In electrical switches of the type described, an electrical contact post comprising two symmetrically-formed pieces of electrically conductive metal rigidly mounted at their lower ends in terminal blocks, the upper ends of said pieces normally bearing against each other and having matching outwardly protruding spherically-rounded portions formed on and protruding from the sides thereof.

2. In electrical switches of the type described,

a ventilated electrical contact post comprising two symmetrically formed members rigidly mounted at their lower ends in spaced relation in a terminal block, the upper ends of said members being bent inwardly and mitered for normally bearing against each other, said members further having opposed outwardly presented matching spherical protuberances, each such protuberance being provided upon its contact surface with a silver contact insert.

3. In electrical switches of the type described, a ventilated electrical contact post comprising two symmetrically-formed members rigidly mounted at their lower ends in spaced relation in a terminal block and being at their upper ends bent inwardly providing end portions having mitered inner faces disposed in abutment against each other, said members further having opposed outwardly protruding spherically-rounded portions, each such protruding portion being provided at its contact surface with a silver contact insert.

4. In electrical switches of the type described, an electrical contact post comprising two symmetrically-formed members rigidly mounted at their lower ends in spaced parallel relation in a terminal block and being at their upper ends bent inwardly providing end portions having mitered inner faces disposed in abutment against each other, said members further having opposed outwardly protruding portions, each such protruding portion being provided at its contact surface with a silver contact insert.

5. A ventilated switch post comprising a base member having two spaced parallel slots, and a pair of identically shaped plates having flat lower portions sized for snug fitting disposition within the slots respectively and projecting upwardly therefrom in spaced parallel and marginally aligned relation to each other, said plates being angularly bent over at their upper ends and mitered providing end faces, said end faces being in abutment against each other whereby to provide an upwardly pointed end for the post and at the same time hold the lower portions of the plates in spaced parallel relation for substantially their entire length, said plates being provided upon their outwardly presented faces respectively with matching protuberances providing oppositely presented contact points.
